(57) **CLAIM**

The ornamental design for a windshield wiper cover, as shown and described.

DESCRIPTION

FIG. 1 is a right side perspective view of a windshield wiper cover.

FIG. 2 is a left side view thereof;

FIG. 3 is a rear view thereof;

FIG. 4 is a front view thereof;

FIG. 5 is a bottom view thereof; and,

FIG. 6 is a top view thereof.

In the drawings, the broken lines depicting a windshield wiper and a portion of the windshield form no part of the claimed design.
